COMBINED IRONING BOARD COVER AND
IRON PAD

Fred Galbraith, New York, N. Y.

Application November 12, 1948, Serial No. 59,713

4 Claims. (Cl. 38—107)

1

This invention relates to new and useful improvements in a combination ironing board cover and iron pad.

More particularly, the invention proposes a new and improved combination as above, and one characterized by the fact that while the iron pad is carried by the cover all the while the cover is on the ironing board, the pad may at will be instantaneously changed in location, either for lying flat on the cover, as at one end of the ironing board, for instance, at the butt or wider end of the board, or for hanging from and outwardly of the board, and so temporarily out of the way and hence then to render the entire length of the board available for pressing and/or spotting a garment or other article to be ironed which, as is often the case, is longer than merely that portion of the board beyond the pad when said pad is at its first-named location, that is, lying flat on the board in position to have a pressing iron rested on the pad.

In accordance with the invention, the iron pad may be constructed of any suitable material or materials, such as asbestos, metal, a plastic and other fire-proof or adequately heat-resistant materials or the like, for protecting the cover against burning or scorching when the pad is lying flat on the board and the pressing iron is ordinarily resting thereon as while a garment or other article to be pressed is being adjusted on the board.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view, showing a conventional type of folding ironing board with the ironing board proper thereof equipped with a now favored embodiment of the invention, and with the iron pad shown in full lines as lying flat on the cover and shown in dot and dash lines as in its other location.

Fig. 2 is an enlarged fragmentary detail view, this being a vertical section taken substantially on the line 2—2 of Fig. 1.

Fig. 3 is a top plan view of Fig. 2.

Fig. 4 is a view similar to Fig. 2, but with the iron pad in its said other location, that is, hanging from an end of the board.

Fig. 5 is an end elevational view, looking toward the left in Fig. 4.

Fig. 6 is an enlarged fragmentary detail view,

2

this being a section taken on the line 6—6 of Fig. 3.

As will be noted, Figs. 3 and 5, although drawn to a larger scale than Fig. 1, are drawn to a somewhat smaller scale than Figs. 2 and 4.

The ironing board 10 is illustrated as of the familiar shape and as of the type including a collapsible under structure 11 to provide a so-called folding ironing board.

10 The ironing board cover forming part of the new combination is designated 12, and the same is illustratively shown as of the accepted kind incorporating suitable portions and/or additions (in the latter case, for instance, a tying tape or cord, not shown), whereby such cover at its main expanse may be tautly stretched over the upper surface of the board 10 and then include other portions for lying opposite the bounding edges of the board and further including marginal extensions such as the one indicated at 14 in Figs. 2 and 4 at the butt end of the board 10 for being inturned for disposition against the bottom surface of the board incidental to attaching the cover to the board.

23 The pad 15, for lightness, durability and a high fire-resistant quality, desirably may be made, as indicated, of a self-sustaining sheet or slab of a suitable material; the now preferred material being the fabricated product known as asbestos board. As shown, such slab is of elongate rectangular shape.

The pad 15 is swingably mounted on the cover 12 by a flexible hinge means indicated generally at 16. Such hinge desirably incorporates one or more strips of a pliant material, as a textile material, which latter may be the same material as used for making the cover 12.

As herein shown, two of such strips are employed, these marked 17 and 18, to provide a two-ply flexible component of the hinge means. The strips 17 and 18 may conveniently be secured along their lengths and in a direction widthwise of the cover 12 by stitchings such as indicated at 19.

45 Further to fortify and strengthen such hinge structure, before said stitchings are applied, the strips 17 and 18 are shown as marginally longitudinally folded to provide inturned seams as shown clearly in Figs. 2 and 4, thereby to establish a four-ply structure along the line or lines of anchorage of the hinge means to the cover 12.

The iron pad 15, as already stated desirably elongated as illustrated, is secured at one of its sides to the free end of said flexible component 50 17—18 of the hinge means, as by use of a suit-

able plurality, here shown as three, of split shank fasteners 22, of a familiar type. These fasteners, usually of soft brass, are commonly spoken of in the stationer's art as split brass fasteners.

Ordinarily, during ironing, the pad 15 may be arranged as in Figs. 1, 2 and 3. However, when an ironing space is desired which is coextensive or almost so with the entire length of the board 16, the pad 15 may be instantaneously lifted, swung at its free end beyond the adjacent end of the board 10, and then allowed to drop temporarily, whereupon the pad depends vertically and completely out of the way, as shown in Figs. 4 and 5, and, in dot and dash lines, in Fig. 1. The cover 12 may be retained on the board, regardless of how many times the described changes of location of the iron pad 15 occur, until the cover is desired to be removed from the board, as for washing. Whenever the cover is to be washed, it is a simple and quick matter to open up the fasteners 22 and remove them, thereby temporarily to disconnect the pad 15 from the cover.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In combination with an ironing board, a cover of cloth material covering the top surface of the board, a hinge of flexible material extended laterally across said cover adjacent one end of the board, stitches securing the outer edge of said hinge to said cover, a pad of rigid material resting on said cover and having its outer edge overlapping the inner edge of said hinge, and means releasably securing together the overlapped outer edge of said pad and the inner edge of said hinge, whereby said pad can be swung on said hinge to depend along the adjacent end of the board.

2. In combination with an ironing board, a cover of cloth material covering the top surface of the board, a hinge of flexible material extended laterally across said cover adjacent one end of the board, stitches securing the outer edge of said hinge to said cover, a pad of rigid mate-

rial resting on said cover and having its outer edge overlapping the inner edge of said hinge, and means releasably securing together the overlapped outer edge of said pad and the inner edge of said hinge, whereby said pad can be swung on said hinge to depend along the adjacent end of the board, said hinge being formed of superimposed layers of cloth material.

3. In combination with an ironing board, a cover of cloth material covering the top surface of the board, a hinge of flexible material extended laterally across said cover adjacent one end of the board, stitches securing the outer edge of said hinge to said cover, a pad of rigid material resting on said cover and having its outer edge overlapping the inner edge of said hinge, and means releasably securing together the overlapped outer edge of said pad and the inner edge of said hinge, whereby said pad can be swung on said hinge to depend along the adjacent end of the board, said pad being formed of asbestos board and being of a width slightly less than the width of the ironing board and of a length approximately one-sixth the length of the ironing board.

4. In combination with an ironing board, a cover of cloth material covering the top surface of the board, a hinge of flexible material extended laterally across said cover adjacent one end of the board, stitches securing the outer edge of said hinge to said cover, a pad of rigid material resting on said cover and having its outer edge overlapping the inner edge of said hinge, and means releasably securing together the overlapped outer edge of said pad and the inner edge of said hinge, whereby said pad can be swung on said hinge to depend along the adjacent end of the board, said securing means comprising spaced split fasteners engaged through the overlapped edges of said hinge and said pad.

FRED GALBRAITH.
